UNITED STATES PATENT OFFICE.

THOMAS J. FAY, OF BROOKLYN, NEW YORK, ASSIGNOR TO THE AMERICAN ELECTRIC COLD SUPPLY COMPANY, OF MAINE.

MAGNETIC CLUTCH.

SPECIFICATION forming part of Letters Patent No. 593,571, dated November 16, 1897.

Application filed February 5, 1897. Serial No. 623,029. (No model.)

To all whom it may concern:

Be it known that I, THOMAS J. FAY, a citizen of the United States, residing at Brooklyn, in the county of Kings and State of New York, have invented certain new and useful Improvements in Magnetic Clutches, of which the following is a full, clear, and exact description.

This invention relates to the transmission of mechanical power by means of a magnetic clutch, the object being to provide for the transference of power from one member of the clutch to the other through a stationary diaphragm without experiencing any inefficiency of the clutch due to the creating of extra currents in the diaphragm, which would, if permitted, engender a force counteracting that of the clutch.

To fully explain the nature and utility of my invention it will be necessary to explain the apparatus or machine with which the clutch is associated, and this I will do in the detailed description which follows, reference being had to the accompanying drawing, wherein a general plan of the entire apparatus is shown, certain parts being in section.

A is a hermetically-sealed casing provided on opposite sides with cylinders a , projecting from its walls, but opening into the interior thereof. In each cylinder is a piston a' , provided with a valve a^2 , opening in such a direction that upon the back stroke of the piston gas or air in the chamber or cylinder will pass through and in front of the piston, the valves closing on the return stroke. From the cylinders suitable exit-pipes a^3 lead. An inlet-passage for air or gas is provided at b . The piston-rods a^4 connect, respectively, with eccentric-pins c upon gears e , these gears being fixed upon the opposite ends of a short shaft having its bearing in box d . Directly under the gears e are pinions e , mounted upon a shaft which has a bearing in the same pillow-block upon which box d is fixed. This shaft, which is lettered f , carries at one end a soft-iron cross-head g , constituting the armature of a magnet, as will hereinafter appear. This cross-head is of yoke shape, having two poles facing toward one of the walls of the casing A , in front of which it is adapted to rotate with very slight clearance.

The apparatus inside of the casing A will be recognized at once as a pump adapted to compress the gas which it receives through the inlet b and force it outward through the passages a^3 to any desired point for consumption or use. In some of the arts, such as that of refrigeration, the gases used are obnoxious or pungent, and it is necessary that the machinery and apparatus operating upon it shall not permit its escape into the atmosphere by leakage. It will therefore be understood that a means for driving the pump herein described from an external source of power without perforating the wall of the casing for the passage of a shaft, the bearing of which would always leak more or less, is a great desideratum. Such means have heretofore been invented by me and described in another application, filed September 30, 1896, Serial No. 607,426, the same consisting, essentially, of an electromagnet mounted to rotate with the driving-motor, and whose magnetic flux or path leads through the unperforated wall of the casing and acts upon an armature located therein and carried by the driving-shaft of the pump. The improvement herein pertains to this device.

P is an electromagnet mounted on the end of a shaft q . It consists of a core p and suitable coils p' wound thereon. The core is U-shaped and is arranged with its poles facing toward the wall of casing A directly opposite the soft-iron cross-head g , which constitutes the armature of the magnet. Shaft q is driven by any suitable source of power, the pulley q' representing such source. The magnet and its armature constitute a clutch adapted to connect and disconnect the source of power with and from the pump.

It has been found in practice that the electromagnet in acting through the metallic wall of the case generates therein electric currents, due to the moving magnetic lines of force, which cut it at right angles. These electric currents travel through the diaphragm in circles always surrounding the path of the lines of force or the core of the magnet and are known in the art as "eddy" or "Foucault" currents. A peculiarity of these circular currents is that their direction is always opposed to that of the current in the coils primarily

responsible for their existence. Thus in the clutch the eddy-currents in the interposed diaphragm surround the core of the magnet and circulate in an opposite direction to the current in the coils p . They therefore react upon the magnet-core and tend to nullify the magneto-motive force of the magnet, which means a reduced efficiency. This nullifying effect is most pronounced at high speeds, and the rate of its increase is much more rapid than the rate of increase of the speed, so that with a given magnet a speed is soon reached beyond which the clutch will not transmit the power, and it is proportionally inefficient for the lower speeds. I overcome this difficulty by making the wall of the casing through which the magnetic clutch acts of material whose electrical conductivity is very poor, or, to state it another way, whose electrical resistance is very high—viz., too high to permit the formation of eddy-currents to any appreciable extent. Such a wall or diaphragm is shown at s . It may be of hard rubber, fiber, vitreous material or a composition having similar characteristics, or a special metallic alloy. A diaphragm of such material will not lessen the efficiency of the magnet as a clutch to any appreciable extent and it may

be easily substituted for a portion of the wall of the casing A , the joints being hermetically sealed without difficulty.

It is obvious that a magnetic clutch for the purpose herein set forth may be made in various shapes and have any suitable number of poles and energizing-coils.

Having thus described my invention, I claim—

The combination of a hermetically-sealed case, a machine therein having a main rotating shaft to be driven, a driving-motor and its rotating shaft located outside of said casing, an electromagnetic clutch having its two members mounted respectively on the two rotating shafts, one member being inside the casing and the other outside thereof, an unperforated wall of the casing composed of dielectric material being interposed between the two members of the clutch, and through which the clutching and unclutching of the two rotating shafts is effected.

In testimony whereof I subscribe my signature in presence of two witnesses.

THOMAS J. FAY.
